2,152,557

DESK STAND

Ernest C. Moore and Willis Ray Challoner, Appleton, Wis.; said Moore assignor to Appleton Music Publication, Inc., Appleton, Wis.

Application August 27, 1938, Serial No. 227,204

4 Claims. (Cl. 45—57)

This invention relates to a readily portable collapsible stand designed primarily, when extended to be placed on a child's desk at school for holding sheet music during band or other music instruction classes, but it is to be understood that a stand, in accordance with this invention is for use in any connection for which it may be found applicable and mounted, when extended on supports other than desks.

10 The invention aims to provide, in a manner as hereinafter set forth, a stand for the purpose referred to capable of being expeditiously extended to holding position and releasably retained in such position when mounted on a support, 15 such as a desk.

15 The invention further aims to provide, in a manner as hereinafter set forth, a stand for the purpose referred to which is simple in its construction and arrangement, strong, durable, readily extended and collapsed when occasion requires, folding in a compact manner when desired, thoroughly efficient in the use intended thereby, sustaining sheet music in a manner to be conveniently read by a scholar, light in weight 20 whereby it is readily ported, when desired in a collapsed condition, and inexpensive to manufacture.

25 The invention further aims to provide a stand for the purpose set forth including a sustaining element for holding the music sheets in an upright position before the scholar, a bracing element for and hinged to the sustaining element and shiftable relatively to the latter for bracing it, and an extendible and foldable support for the 30 music sheets hinged to the sustaining element and extended to supporting position simultaneously with the shifting of the bracing element to bracing position relative to the sustaining element.

35 The invention further aims to provide the supporting element aforesaid with means coacting with the bracing element aforesaid for holding the sustaining element aforesaid in an upstanding position when the stand is extended.

40 Embodiment the foregoing aims and to others which may directly or indirectly hereinafter appear, the invention consists of the novel construction, combination and arrangement of parts which will be more specifically referred to and 45 as illustrated in the accompanying drawing, wherein is shown an embodiment of the invention, but it is to be understood that changes, variations and modifications may be resorted to which fall within the scope of the invention as claimed.

In the drawing:

Figure 1 is a front elevation of the stand when collapsed,

Figure 2 is a side elevation of the stand when collapsed,

Figure 3 is a side elevation of the stand when extended for mounting on a desk or other support,

Figure 4 is a fragmentary view upon an enlarged scale and in side elevation when the stand is extended,

Figure 5 is a fragmentary view, upon an enlarged scale and in side elevation illustrating the position of the supporting element prior to its complete extension by the bracing element,

Figure 6 is a section on line 6—6 Figure 1, and

Figure 7 is a section on line 7—7 Figure 3.

The stand includes a sustaining element 1, a hinged bracing element 2, a hinged supporting element 3, a securing element 4 and a combined pulling and coupling element 5. The elements 1, 2, 3 and 4 preferably will be constructed from cardboard of the desired thickness and rigidity, but it is to be understood that such elements may be formed from any suitable material.

The element 1 is of rectangular contour and of the desired length and width. When element 1 is active, it is disposed in an upstanding manner and inclines rearwardly from its bottom to its top. The purpose of element 1 is to sustain the music sheets in an upstanding rearwardly inclined position so the music may be conveniently read by the scholar.

The bracing element 2 is of truncated tapered form, has a straight top edge 6 and a straight bottom edge 7. The latter is of greater length than edge 6. The element 2 is of less length than the length of 1 and is arranged rearwardly of the element 1. Element 2 has its top edge 6 spaced from and arranged below the upper lengthwise edge 8 of element 1 and its bottom edge 7 spaced from and arranged above the lower lengthwise edge 9 of element 1.

Secured to the rear face of element 1, below and in proximity to edge 8, as well as being disposed centrally of such face is a spacer strip 10. Spaced holdfast means 11 are employed for securing the strip 10 to element 1. The top edge 6 of element 2 is arranged in juxtaposition to the bottom edge of strip 10. The latter is preferably formed of cardboard and is of a thickness corresponding to the thickness of element 2. The latter is hinged to the strip 10 by any suitable means, such as a strip of thin fabric 12 secured to the rear surfaces of the element 2 and strip 10 by any suitable ad-

hesive material. The hinge between element 2 and strip 10 preferably will be provided by a length of adhesive tape.

The supporting element 3 is of oblong form, 5 arranged forwardly of and has its side edges flush with the side edges of the element 1. The lower lengthwise edge 13 of element 3 is arranged above and in proximity to the edge 7 of element 1. When element 3 is extended with respect to element 1 its lower lengthwise edge 13 abuts the front surface of element 1 above the edge 7 of the latter. When element 3 is extended it is disposed at an upward inclination with respect to element 1 (Figure 4) and constitutes a support for 10 the music sheets. The latter at their lower edges are mounted on the upper surface of element 3.

The element 3 is hinged to element 1, by a strip 14 of thin fabric which is of a width to extend in close proximity to the side edges of 20 the elements 1 and 3. A portion of the strip 14 is positioned to oppose a part of the front surface of element 1 and its remaining portion positioned to oppose the inner part of the upper surface of the element 3. The strip 14 is secured 25 to the elements 1 and 3 by any suitable adhesive material. The strip 14 will not only constitute a hinge for section 3, but further connects the latter to section 1. The section 3 when the stand is collapsed folds against the front surface of section 1. The strip 14, if desired, may consist 30 of a length of adhesive tape of suitable width.

The securing element 4 is of oblong form, of a length less than the length of and of a width corresponding to the width of element 3. The 35 element 4 has its lower lengthwise edge 15 flush with the lower lengthwise edge 13 and its side edges flush with the side edges of element 3. The element 4 is secured against the inner part of the lower surface of element 3 by the spaced holdfast means 16. The upper surface of element 4 centrally thereof is grooved, as at 17 for a purpose to be referred to. The lower lengthwise edge 15 of element 4, when the element 3 is extended relative to element 1 has a part 40 thereof abut the front surface of element 1 below element 3. The element 4 depends with respect to element 1 and when the latter is arranged in sustaining position, for the music sheets, it is supported in such position by the lower inner corner 17a of element 4. The groove 45 17 opens forwardly.

The combined pulling and coupling element 5 consists of a tape of the desired width, length and thickness. The rear end terminal portion 55 of element 5 is folded upon itself, as at 18, and is arranged centrally of the lower part of the rear surface of element 2. The folded rear end terminal portion 18 of element 5 is secured to the element 2 by the holdfast means 19. The element 5 extends across the bottom edge of element 2 and the lower inner corner of element 4 when the stand is extended. The forward end terminal portion 20 of element 5 is arranged in the groove 17 and it is fixedly confined between elements 3, 4. The element 5 extends across the forward lengthwise edge of element 4 and when the stand is extended, element 5 not only binds against such edge, but also against the lower surface of element 4, lower inner corner 17a of the latter and the bottom edge of element 2.

It will be assumed that the stand is in collapsed or folded position, such as shown in Figure 2 and it is desired to extend it. The bracing element 2 is moved rearwardly at an inclination 70

with respect to the element 1 or the latter moved forwardly at an inclination with respect to element 2, preferably element 2 will be moved rearwardly with respect to element 1, as element 2 moves rearwardly element 5 will be stretched 5 causing it to assume the position shown in Figure 5, that is against the bottom edge of element 1, a further rearward movement of element 2 will provide for elements 3 and 4 to assume the position shown in Figure 4, and at 10 which point the stand will be extended to the position shown in Figure 3, with the element 1 coupled with the element 2 by the element 5 and held in an upstanding rearwardly inclined position, and with the element 3 held in a forwardly extending upwardly inclined position relative to element 1. When the elements 1 and 3 are in the inclined positions as aforesaid, they act respectively to sustain and support the music sheets when the stand is in extended position 20 and mounted on a desk or other support, and at the same time, the weight of the article or articles supported by the stand will be applied to elements 3, 4, the top of element 2 and the bend 20 of element 5 whereby the latter will be 25 held taut, and the stand maintained in extended position when used. The stand, when in use will not only be mounted on the corner 17a of element 4, but also on portion 21 and bend 22 of element 5. From the foregoing, it is readily 30 obvious that the weight of the article mounted on the stand tends to maintain the latter in extended position.

What I claim is:

1. In an extendible and collapsible stand, a 35 sustaining element, a shiftable bracing element hinged with the rear face of the sustaining element, a supporting element hinged at its rear to the front surface of, spaced above and arranged in proximity to the bottom edge of said sustaining element, a bendable combined pulling and coupling element arranged below the bottom edges of the sustaining and bracing elements and having its rear end terminal portion anchored to the back of said bracing element, 40 said coupling element having its forward end terminal portion positioned against the lower surface of the supporting element, and a securing element secured to the lower face of the supporting element, bearing against parts of said coupling element adjacent said forward end terminal portion and providing for fixedly confining the forward end terminal portion of the combined pulling and coupling element between 45 said securing and supporting elements. 50

2. In an extendible and collapsible stand, a 55 sustaining element, a shiftable bracing element hinged with the rear face of the sustaining element, a supporting element hinged at its rear to the front surface of, spaced above and arranged in proximity to the bottom edge of said sustaining element, a bendable combined pulling and coupling element arranged below the bottom edges of the sustaining and bracing elements and having its rear end terminal portion anchored to the back of said bracing element and, 60 said coupling element having its forward end terminal portion positioned against the lower surface of the supporting element, a securing element secured to the lower face of the supporting element, bearing against parts of said coupling element adjacent said forward end terminal portion and providing for fixedly confining the forward and terminal portion of the combined pulling and coupling element between 65 70 75 80 85 90 95 100

said securing and supporting elements, said securing element being of a thickness and so disposed relative to the sustaining element whereby when the stand is extended said supporting element will depend below the bottom edge of the sustaining element and constitutes a support for the latter.

3. In an extendible and collapsible stand, a sustaining element, a shiftable bracing element hinged with the rear face of the sustaining element, a supporting element hinged at its rear with the front surface of, spaced above and arranged in proximity to the bottom edge of the sustaining element, a bendable combined pulling and coupling element arranged below the bottom edges of the sustaining and bracing elements and having its rear end terminal portion anchored to the back of said bracing element centrally of the lower portion of said back, said 10 pulling and coupling element having its forward end terminal portion reverted and positioned against the lower face of the supporting element centrally of such face, a securing element anchored to the lower face of said supporting element and having a groove in its upper face receiving said forward end terminal portion, the latter being fixedly confined by said securing element between said supporting and securing elements, and such securing element being of a

thickness to abut and depend below the sustaining element when the stand is extended to depend below the bottom edge of and constitutes a support for the sustaining element.

4. In an extendible and collapsible stand, a sustaining element, a bracing element for, shiftable relative to and hinged to the sustaining element, a combined pulling and coupling element arranged below the bottom edges of the said other elements and having a rear end terminal portion secured to said bracing element, a supporting element hinged to the front surface of the sustaining element, a securing element anchored to the lower face of the supporting element, said combined pulling and coupling element having a part disposed against the lower face and forward surface of the securing element and a reverted forward end terminal portion interposed between the securing and supporting elements, said securing element fixedly anchoring said reverted portion between the supporting and securing elements, and said securing element being so related to the sustaining element to constitute a support for the latter when the stand is extended and to bind on the combined pulling and coupling element. 15 20 25
